UNITED STATES PATENT OFFICE.

JOHN J. WAY, OF EDGEWORTH, PENNSYLVANIA.

SAFETY DEVICE FOR CONTROLLERS.

Application filed May 18, 1921. Serial No. 470,538.

To all whom it may concern:

Be it known that I, JOHN J. WAY, a citizen of the United States, residing at Edge-
worth, in the county of Allegheny and
5 State of Pennsylvania, have invented cer-
tain new and useful Improvements in
Safety Devices for Controllers, of which the
following is a specification.

This invention relates to controllers such
10 as those used in connection with various ve-
hicles and motor driven machinery, and is for
a safety device which will render it impos-
sible to move the controller from a neutral
position without first closing a safety cir-
15 cuit.

An object of this invention is to provide
a magnetically controlled means between
the operating handle of a controller and the
movable member of the controller, such as
20 the contact closing device in an electric con-
troller, arranged so that the operation of the
handle will not move the said controller
member unless a safety circuit is closed.

Further objects are to provide a device
25 of this kind in which there is normally no
movement of the parts so that there is little
liability of trouble or of parts wearing out,
and a device which will automatically allow
30 the controller mechanism to move to neutral
position if the safety circuit should at any
time be opened when the controller mecha-
nism is in operative position.

One embodiment of my invention is shown
in the accompanying drawing in connection
35 with an elevator controller. In the draw-
ings:

Fig. 1 is a rear view of an elevator con-
troller of any well known or preferred type,
showing my invention applied thereto;

40 Fig. 2 is a side elevation, showing part
of the operating lever and controller in sec-
tion;

Fig. 3 is a diagrammatic view represent-
ing a circuit which may be used in connec-
45 tion with elevators.

In the drawings, A represents an elevator
cage having a side wall 5 and a controller
casing 6 mounted on a bracket 7. B repre-
sents an elevator shaft and C the doors.

50 In the casing 6 is a rotatable shaft 8
which carries the usual circuit closing or
contact member. One end of the shaft pro-
jects outside the casing and has a threaded
end 9. On the projecting end of the shaft 8
55 and retained in place by a suitable nut 9' is
the hub 10 of an operating lever or crank

11. At the outer end of the lever is a handle
11'. The hub 10 is freely rotatable about
the shaft 8.

Suitably mounted on the operating crank 60
11 is an electro-magnet, such as a pair of
coils 12 having suitable supporting means
13 and poles 14. At 15 is an armature
adapted to be attracted by the magnets, and
secured to the armature at 16 is a vertical 65
pin or plunger 17 which is slidably carried
in the supporting means 13, and which has
a rounded lower end 18 adapted to be passed
through and guided in the hub 10. In the
shaft 8 is a rounded or concaved recess in 70
which only the rounded end 18 of pin 17 may
be projected. The arrangement is such that
when the armature 15 is against the ends of
poles 14, the rounded end 18 of the pin pro-
jects into the recess. 75

Surrounding the pin 17 and interposed
between a washer 19 secured thereon and
one of the supporting members 13 is a com-
pression spring 20 which normally urges
the end of the pin into the recess, and which 80
is preferably relatively weak.

The controller 6 may be provided with
the usual double acting spring 21 secured
85 to shaft 8 and adapted to return the con-
troller parts to neutral position, if the oper-
ator should ever from any cause release the
handle when the car is moving or when the
controller parts are moved to operative posi-
tion. This spring is generally quite stiff.

In operation, if an effort is made to ro-
tate shaft 8 to bring the contact members
into operative position before the magnets
12 are energized, the spring 21 will resist
such movement, and the rounded end 18 of
the pin 17 will ride out of the concave recess and
90 the lever 11 will not transmit any motion
to shaft 8. When the magnets are ener-
gized and the armature 15 is across the poles
14, the pin 17 will not lift out of the re-
cess, it, of course, being appreciated that
95 the pull of the magnets, where the armature
is actually across and in contact with the
poles, is considerable. The shaft 8 may ac-
cordingly be rotated. Should the circuit be
broken while the parts are in operative
100 position, spring 21 would overcome the
pressure exerted by spring 20 alone, and
the shaft 8 would be rotated to neutral posi-
tion, independently of the handle.

110 In Fig. 3, the diagram illustrates the mag-
nets 12 connected in a circuit which has con-
tacts & therein adapted to break the circuit

when the doors C are open and close it when the doors are closed. Contacts of this kind are common in the art. The current lines for the door contacts are indicated at 5 *b* and *b'*. *D* represents a magnetic switch also energized from lines *b* and *b'*. Contacts *a* are located in line *b*, and at *c* the circuit is divided. Line *d* passes down to one side of the coil of switch *D*, the other side of 10 which connects directly to the line *b'*. Line *e* passes through the magnets 12, and connects to line *b'* at *e'*. Switch *D* is adapted to close and break a circuit through the elevator control lines *f* and *f'*. Thus, it will 15 be seen that if any or all of the doors C are open, the circuit through the magnets 12 is broken and the circuit through switch *D* is open, and it is not possible to operate the elevator.

20 An emergency circuit *g* through push button *h* in the car may be provided to short circuit around the door contacts *a*, but this button, as is usual with emergency buttons, is so arranged and positioned that the operator must use both hands to run the car 25 when using it.

From the foregoing, it may be seen that there is no relative movement between parts except when the operator moves the control 30 lever 11 with the circuit through magnets 12 open, or when the circuit is broken at a time when the controller is moved to operative position. Furthermore, it may be especially noted that pin 17 does not, in the arrangement shown, move up and down every time the safety circuit is opened.

It will be obvious that the device need not be limited to use in connection with elevator controllers, as it may be used on various 40 types of electric or steam, or other controllers, such as on vehicles of various kinds, or in connection with traveling cranes or hoisting machines, and other apparatus. Various changes and modifications may also 45 be made in the particular construction shown.

What I claim is:

1. The combination with a controller having a movable member and an operating 50 member for effecting the movement thereof, of magnetically controlled means carried by one of said members having means for cooperation with the other member for normally retaining the operating member in operative connection with the movable member.

2. The combination with a controller having a movable member and an operating member, magnetically controlled means on 60 one of the members for normally retaining the operating member and movable member in operative connection, said magnetically controlled means including an electro-magnet and a means cooperating with the 65 magnet which yieldably holds the parts in

normal position but which is insufficient to hold them in normal position upon movement of the operating member when said magnet is de-energized.

3. The combination with a controller having a movable member having neutral and operating positions and means for urging the movable member to neutral position, an operating member for effecting the movement of the movable member, of a magnetically controlled means carried by one of said members and including an electro-magnet for normally retaining the operating means and movable member in operative connection but for permitting relative movement between the operating means and movable means upon the de-energization of the electro-magnet.

4. The combination with a controller having a movable member which has a neutral and an operating position and is provided with a spring for holding it in or returning it to neutral position, of an operating handle movable relatively to the movable member, magnetic means including an electro-magnet 90 for normally holding the operating handle and movable member against relative movement when the magnets are energized, and a second spring associated with the said magnetic means for holding said means in 95 normal position but allowing said means to be moved out of normal position and permit relative movement of the handle and movable member, whereby the said movable member will always be moved or retained 100 in neutral position when the magnet is de-energized.

5. A controller having a rotatable shaft and an operating means freely movable thereon, a magnetically operated pin on the operating means and an electro-magnet therefor adapted to enter a recess in said shaft to hold the shaft and operating means against relative movement and so arranged that it may be disengaged from the recess 105 to permit relative rotation of the shaft and operating means when the electro-magnet is de-energized.

6. A controller having a rotatable shaft, an operating means freely rotatable thereon, a reciprocable pin on the operating means having a rounded end adapted to be projected into a rounded recess on said shaft, a spring for yieldably urging the pin into the recess, an electro-magnet on the operating 115 means having an armature connected with said reciprocable pin for holding the pin in the recess when the magnet is energized.

7. The combination with a controller having a movable member and an operating member therefor movable relatively thereto, of locking means carried by one of the members cooperating with the other member for normally holding said movable member and operating member against relative move- 125 130

ment, and means whereby said locking means may be automatically released.

8. The combination with a controller having a movable member and an operating member therefor movable relatively thereto, of a movable locking means carried by one of the members for engaging the other member to normally hold them against relative movement, and means whereby said locking

means may be moved to engage or disengage 10 said members.

In testimony whereof I affix my signature in presence of two witnesses.

JOHN J. WAY.
